CLAIM

The ornamental design for a clothes hanger, as shown and described.

DESCRIPTION

FIG. 1 is a front perspective view of a clothes hanger showing my new design.

FIG. 2 is an elevational view from the front; the rear view being a mirror image thereof.

FIG. 3 is an elevational view from the bottom thereof; and, FIG. 4 is an elevational view from the front, in an alternative position.

The broken line showing of a hanging hook is for illustrative purposes only and forms no part of the claimed design.
